Primary Examiner — Leanne Was-Englehart*(74) Attorney, Agent, or Firm* — Saidman DesignLaw Group, LLC(57) CLAIM

The ornamental design for a theater, as shown and described.

DESCRIPTION

The sole FIGURE is a perspective view of a theater showing our new design.

The evenly spaced dashed lines depict portions of the theater and environment which form no part of the claimed design. The dot-dash broken lines depict unclaimed boundaries and form no part of the claimed design.
